UNITED STATES PATENT OFFICE.

CHARLES A. BENNETT, OF TAUNTON, MASSACHUSETTS, ASSIGNOR TO
REED AND BARTON CORPORATION, OF TAUNTON, MASSACHUSETTS.

DESIGN FOR A FORK, SPOON, OR SIMILAR ARTICLE.

SPECIFICATION forming part of Design No. 37,141, dated September 20, 1904.

Application filed July 28, 1904. Serial No. 218,555. Term of patent 14 years.

To all whom it may concern:

Be it known that I, CHARLES A. BENNETT, of
Taunton, in the county of Bristol and State of
Massachusetts, have invented a new, original,
and ornamental Design for Forks, Spoons, or
Similar Articles, of which the following, taken
in connection with the accompanying draw-
ings, is a specification.

Figure 1 illustrates a front elevation of a

fork or spoon embodying my design, and Fig. 10
2 represents a side elevation.

I claim as my invention—

The ornamental design for a fork, spoon or
similar article, as shown.

CHARLES A. BENNETT.
